C. R. SHORT.

OIL LEVEL INDICATOR FOR MOTOR VEHICLES.

APPLICATION FILED APR. 6, 1917.

1,386,903.

Patented Aug. 9, 1921.

INVENTOR:

CHARLES R. SHORT,

BY

Charles R. Short
ATTORNEY.

UNITED STATES PATENT OFFICE.

CHARLES R. SHORT, OF DETROIT, MICHIGAN, ASSIGNOR TO GENERAL MOTORS COMPANY, OF DETROIT, MICHIGAN, A CORPORATION OF NEW JERSEY.

OIL-LEVEL INDICATOR FOR MOTOR-VEHICLES.

1,386,903.

Specification of Letters Patent.

Patented Aug. 9, 1921.

Application filed April 6, 1917. Serial No. 160,127.

To all whom it may concern:

Be it known that I, CHARLES R. SHORT, a subject of the King of Great Britain, and resident of Detroit, Wayne county, State of Michigan, have invented certain new and useful Improvements in Oil-Level Indicators for Motor-Vehicles, of which the following is a specification.

This invention relates to hydrocarbon motors, and particularly to liquid level gages therefor.

In the usual construction of a hydrocarbon motor power plant, wherein the crank case is split horizontally in approximately the median plane of the crank shaft, forming an upper and lower section, it is usual to have an oil gage actuating mechanism arranged in the lower section of the crank case with an integral or non-detachable indicator stem 20 arranged within the upper section of the crank case, at a point considerably above where the sections are joined. With such constructions, when it is found desirable to remove the lower section of the crank case 25 from the upper section, it is necessary to drop the former until the upper end of the indicator stem has been lowered to or below where the sections meet. This construction frequently results in causing considerable 30 difficulty in dis-assembling the lower section of the crank case from the upper, because in many instances facilities do not permit the necessary clearance for dropping down the lower crank case section.

To obviate these, and other difficulties, and to compensate for variations of manufacture, which would result in mis-alinement with the ordinary constructions, I have provided a gage actuating an indicator mechanism 40 having portions mounted in each section of the case and either abutting against one another while having no other connection, or having detachable connections which facilitate the dis-assembly of one crank case 45 section from another, without the extreme movements necessary for separating these sections in the usual construction.

These, and other objects, will clearly appear from the following description, taken 50 in connection with the accompanying drawings, which form a part of this specification, and in which:

Figure 1 is a transverse vertical section of a portion of a hydrocarbon motor crank 55 case, embodying a form of my invention;

Fig. 2 is a section similar to Fig. 1, illustrating only the upper section of the crank case;

Fig. 3 is a detail of the gage indicator stem;

Fig. 4 is an end elevation with a portion broken away of the crank case lower section; and

Fig. 5 is a fragmentary section similar to Fig. 2 of a modified form.

Referring to the drawings, 10 illustrates the upper half of a motor crank case section in which a crank shaft 11 may be mounted in suitable bearings. The lower section of the crank case, sometimes known as the oil pan 11^a, may be joined to the upper half in the median plane of the crank shaft and maintained in position as by bolts 12. Arranged in the pan 11^a, a short distance above its bottom portion is a transverse wall 13 on 70 which is supported an arm 14, having a boss 15 through which a float stem 16 extends. A float 17 which is adapted to be partially immersed in a lubricant 18 confined in the bottom of the pan 11^a is suitably secured to the 75 lower end of the member 16. A diaphragm or plate 19 is mounted at the upper end of the stem.

An indicator stem 20 is adapted to be slidably mounted in a boss 21 formed in 85 the upper section 10 of the crank case. The pointer 22, which is formed on the upper end of this stem, is located in proximity to a recessed portion of the crank case member 10, which is provided with graduations 90 as at 23 in either inches or liquid measure, so that when the lower end 24 of the stem 20 rests against the upper end 19 of the float stem 16, the position of the pointer 22, relative to the graduation 23, will indicate the 95 level of liquid in the pan 11^a.

This oil gage construction, permits lateral variations of the relative position of the upper and lower section of the gage, and the oil pan may be dis-assembled from the upper 100 half of the crank case and returned to position in a very simple and easy manner.

Referring to Fig. 5, it is to be noted that the upper end of the stem 16 is provided with an interiorly threaded cup 25 and the 105 lower end of the indicator stem 20 is exteriorly threaded for detachably connecting these parts. The boss 15 of the arm 14 may be provided with a pair of stops 27 which co-operate with the transversely arranged 110

pin 28 on the stem 16 for preventing rotation of this stem relative to the indicator stem 20, when the latter is threaded to or unthreaded from the former.

5 While I have described, and will specifically claim, what I deem to be preferred forms of my invention, it will be obvious to those skilled in the art, that various modifications and changes may be made without departing from the spirit and scope hereof.

10 Having thus described my invention, what I claim and desire to secure by Letters Patent is:

1. In combination with a container having two parts detachably secured together, a gage device comprising a float operated member located within one part of said container and permanently associated therewith, and an indicating member carried by the other part of said container and abutting against but unconnected with said first mentioned member.

2. In an internal combustion engine, a crank case having upper and lower sections detachably connected together, and an oil level indicating device comprising float operated mechanism located within the lower of said sections, and an indicating member associated with the upper of said sections; said float operated mechanism being in operative engagement with and separable from said indicating member.

3. In an internal combustion engine having a two part crank case, a gage comprising a float actuated member mounted in one part of said crank case, and a second mem-

ber mounted in the other part of said crank case and adapted to be operated by said float actuated member and having a non-permanent connection therewith.

4. In an internal combustion engine, a crank case having two parts detachably connected, an indicator stem mounted in one part, a float mechanism mounted in the other part, said stem being adapted to merely rest on a movable part of said mechanism and to be actuated thereby.

5. In an internal combustion engine, in combination with a crank case having a plurality of parts detachably connected, a float mechanism comprising an actuating stem mounted in one of said parts and an indicator stem mounted in another part, said latter stem being adapted to rest on said former stem and to be actuated thereby.

6. In combination in an internal combustion engine having a crank case comprising upper and lower sections secured together and the lower of which sections is separable from the upper, and which upper section is provided with a recess; a vertically movable reciprocating rod extending through a guide carried by said upper section and the upper end of which moves within said recess; a float located within the lower of said sections; and an actuating member carried by said float and movable therewith and which member is in operative but non-permanent engagement with said rod to thereby communicate motion thereto.

In testimony whereof I affix my signature.

CHARLES R. SHORT.
